UNITED STATES PATENT OFFICE

NELS P. PETERSEN, OF LOS ANGELES, CALIFORNIA

SLUG EJECTOR FOR COIN MACHINES

Application filed July 2, 1926. Serial No. 120,125.

My invention is a slug ejector for coin machines, adapted to either discharge or to return so-called slugs or other devices which a person may attempt to pass for a coin.

5 An object of my invention is the construction of a slug ejector for use with coin controlled machines adapted to throw out coins which have magnetic properties, those having smooth faces and rims and those having 10 holes in the center.

Another object of my invention is to construct a slug ejector which will properly handle a legitimate coin to operate the coin controlled machine and will return the slugs 15 or like constructions to the operator of the machine.

A further object of my invention is a slug ejector in which coins having magnetic properties are discharged from the chute in which 20 they are inserted and have means by which slugs having magnetic properties are forced into engagement with the magnet and thereby guided into a discharge chute for magnetic slugs.

25 A still further object is the construction of a slideable type of coin block containing a pocket for coins and having means in said block to grip and hold coins by the bead or rim around the edge, such gripping mechanism failing to hold smooth surface slugs and allowing these to drop in the travel of the block, into a slug ejecting chute; The machine is provided with means for disengaging the coin holding device and allowing 15 coins to drop in a coin chute.

Slugs which have a bead on the edge and a hole in the center are disengaged from the holding device after passage of the slug chute and are retained by a stopping device 0 engaging the central aperture, thereby limiting the movement of the coin block so that it is not positioned over the coin chute. On the return movement the gripping device fails to engage such slug with a rim and a 5 hole as these have been slightly dropped and such slugs are moved in the slug chute and discharged.

Another object of my invention is in providing a delay action or a slight stop when 0 the sliding coin block is positioned over the

slug chute, giving time for said slugs to drop into the slug chute and prevent their being carried on, no matter how rapid the action of the machine be.

My invention may be considered as a 55 modified form of slug ejector as shown in my patent application Serial No. 103,221, filed April 20, 1926, some of the features being in common, the present invention however, has in addition means to institute the 60 positive ejection of a slug and means to prevent insertion of coins or slugs in the coin block before same is properly positioned.

Other detail features will be apparent 65 from the description.

My invention will be more readily understood from the following description and drawings, in which;

Figure 1 is a side elevation with the casing partly broken away, of my slug ejector; 70

Fig. 2 is an end elevation of Fig. 1, taken in the direction of the arrow 1 of Fig. 2;

Fig. 3 is a vertical longitudinal section taken on the line 3—3 of Fig. 2 in the direction of the arrows; 75

Fig. 4 is a vertical transverse section taken on the line 4—4 of Fig. 3 in the direction of the arrows, with the casing removed;

Fig. 5 is a view similar to Fig. 3, showing the coin block in another position; 80

Fig. 6 is a vertical cross section on the line 6—6 of Fig. 5, illustrating the manner of suspending the coin;

Fig. 7 is a horizontal section on the line 7—7 of Fig. 5 in the direction of the arrows; 85

Fig. 8 is a horizontal section on the line 8—8 of Fig. 5, in the direction of the arrows;

Fig. 9 is a horizontal section on the line 9—9 of Fig. 5, indicating the coin block moved to a further position and with a slug 90 having an aperture suspended therein;

Fig. 10 is a horizontal section on the line 10—10 of Fig. 5 in the direction of the arrows;

Fig. 11 is a perspective view of the coin block viewed from above and from one end; 95

Fig. 12 is a perspective view of the coin block viewed from below and from the opposite end to that of Fig. 11.

The stationary housing for the slug ejector 100

mechanism is constructed substantially as follows:

The housing is designated generally by the numeral 1, being preferably in two longitudinal halves formed substantially the same and attached together by screws or the like. The upper portion 2 contains an insert coin chute 3, this chute having an inclined passage 4 followed by a substantially vertical drop passage 5. A permanent magnet 6 is mounted on a lug 7 and a chute 8 for slugs having magnetic properties is positioned below the magnet, discharging at the front of the machine. A guideway designated generally by the numeral 9 extends lengthwise of the housing or block and preferably has a plug 10 forming a closure for the forward end, this plug being attached by a set screw 11 or the like.

20 A slug chute 12 is formed in the housing back of the coin drop passage 5 and still further rearwardly a coin chute 13 is formed. An insert plate 14 preferably of hard metal is positioned below the coin drop passage 5 and extends upwardly above the base 15 of the guideway 9. A wear plate 16 is inserted adjacent the slug chute and its upper surface is in alinement with the base 15 of the guideway. One side of the guideway is provided with a longitudinal passage 17 and has a slot 18 extending part of the length of the housing and extending into the passage 17. The upper portion of the guideway has bearing surfaces 19 for the coin block as hereunder described and with a roof section 20 located above the top of any coin which might be inserted in the machine.

The side portions 21 of the guideway are to accommodate holding or retaining devices for the coins as hereunder described. The housing is supported by lugs 22 or the like at the base which may be secured to a coin controlled machine of any suitable type.

45 The sides of the housing are provided with forward cam surfaces 23 and rearward cam surfaces 24, these being preferably hard metal inserts into the side portions 21 of the guideway for controlling the operation of the suspending fingers or dogs for coins as hereunder set forth in detail.

A recess 25 is formed in one of the housing sections and a lever 26 is pivoted on a vertical pin 27. This lever has a small roller 28 at one end and a compression spring 29 positioned between such end of the lever having the roller and the side of the housing. A slideable pin 30 is fitted through an aperture 31 in the lever, this pin being normally pressed towards the guideway by the leaf spring 32, and passing through the slot 32'.

The housing sections have a socket 33 formed in each half and a slug ejector pin 34 extends downwardly into the guideway.

This pin has a head 35 resting in the bottom 36 of the socket and is pressed downwardly by a compression spring 37.

A coin retainer pin 38 is slideable in a longitudinal slideway 39, this being formed in each half of the housing and having a compression spring 40 normally forcing same into the coin passage 5 as shown in Fig. 5. The pin has a depending arm 41 to engage the coin block as hereunder set forth.

The coin block is designated generally by the numeral 42 and has a web section 43, an upper flange section 44 and a lower flange section 45 on one side. The block has a slight incline 46 at the rearward end, 47 at the forward end and 48 and 49 at each end of the coin pocket 50 which extend vertically through the coin block. The web of the block is provided with a longitudinal groove 51 at the bottom, this groove sliding over the insert plate 14. A pair of lateral slots 52 extend sidewise from the coin passage and have a pair of dogs or fingers 53 mounted therein, these being swivelled on pins 54. The gripping ends 55 of the dogs extend into the coin pocket 50, the outer ends 56 extend into the side portions 21 of the guideway and are positioned to engage the stationary cams 23 and 24. The lower flange 45 is provided with a screw threaded hole 57 for a pin as hereunder set forth.

The operating mechanism for the slug ejector is constructed substantially as follows, having reference particularly to Figs. 1, 2 and 4:

This illustrates the pausing motion device. An operating arm 58 is mounted on a bolt 59 which is threaded into a lug 60 extending laterally from one side of the housing. A coiled spring 61 secured respectively to the operating arm and to the lug is normally tensioned to hold such arm with the lower end in the forward position as indicated in Fig. 1. This arm has a U-shaped slot 62 at its lower end, having forward and rearward slots 63 and 64 with a joining slot 65. A stud 66 having a small roller 67 thereon extends through this U-shaped slot through the longitudinal slot 18 and is screw threaded into the hole 57 in the flange 45 of the coin block.

The manner of operation of my slug ejector is substantially as follows:

Presuming first that a slug having magnetic properties is inserted in the coin chute 3, this is guided by the inclined portion of the passage 4 so that the edge of the slug is drawn against the magnet 6 substantially at the pole pieces where the magnetic flux is strongest. The magnet thus attracts the slug and causes it to follow the path 8 for slugs having magnetic properties. It does not matter whether the slug is gently placed in the coin chute or vigorously forced there-

in as in both cases the slug is sure to be thrown against the magnet and brought into actual contact with same.

If a legitimate coin is inserted in the coin chute this coin having no magnetic properties follows the inclined path 4 and drops vertically into the lower drop portion 5 of the passage and if the coin block should be in a rearward position the coin is retained elevated by means of the pin 38 which projects into the coin drop passage 5. However, when the coin block is in its normal stationary or initial position as shown in Fig. 3, the coin drops into the coin pocket 50 of the block, the lower edge of the coin resting on the upper edge of the insert plate 14 as indicated in Figs. 3 and 4. In this position the cams 23 hold the dogs 53 so that the gripping ends 55 are moved out of contact with the coin. When the operating arm 58 is drawn forward at its upper end the motion is transferred through the pin 66 connected to the flange 45 to the block and slides the block lengthwise of the housing, as the pin slides upwardly in the rearward slots 64 until it is positioned in the adjoining slot.

During the slight motion of the lever the coin block is stationary until the pin 66 enters the forward slot 63 when the motion is continued. The cams 24 on the side of the housing for opening the suspending dogs are positioned to open such dogs when the coin is slightly past the wear insert plate 16. The coin is then freed and drops on the base surface 15 of the guideway and is shoved into the coin chute 13, thereby following such chute into any coin controlled machine.

Presuming a coin having a smooth edge without any bead and without any central perforation or the like is utilized, this coin being non-magnetic, it drops in the same manner as a legitimate coin through the coin chute into the coin pocket of the coin block but as the suspending dogs do not grip such coin, there being no bead, it is carried by the block until the slug rolls off the upper edge of the insert plate 14. Just at this edge the upper edge of the slug comes into contact with the pin 34 pressed downwardly by the spring 37, being forcibly thrust downwardly into the slug chute 12. At this particular time the pin 66 is traversing the joined section 65 of the U-shaped slot and the block is held stationary for the moment. Therefore this gives sufficient time, no matter how quickly the operating arm is worked and the coin block slid, for the slug to drop clear of the coin block into the slug chute, as there is always this pause or positive stop in the movement of the coin block.

Presuming a slug non-magnetic and having a central aperture with a bead or rim

on the edge is utilized, this falls through the coin chute into the coin pocket of the coin block in the manner above described and the gripping dogs engage such slug by the rim carrying it suspended in the same manner as a legitimate coin, over the coin chute 12 in the backward movement of the coin block. This slug is however, dropped by the dogs engaging the cam 24 as above described so that it rests on the upper surface of the insert 16 on a level with the base 15 of the guideway.

The movement of the coin block rearwardly engages the roller 28 on the lever 26, swinging such lever from the position shown in Figs. 7 and 8 to that shown in Fig. 9 and in such action the pin 30 is thrust by means of the spring 32 into the central aperture of a slug as shown in Fig. 9. When a legitimate coin is used however, the spring 32 gives and allows the coin to be thrust further into the coin chute 13. When the pin 30 is engaging a slug this blocks the movement of the machine preventing the block from being moved back any further. The spring 61 will then draw the block forwardly unless the person operating same voluntarily does this and in such action the coin pocket 50 rolls the slug on the upper edge of the insert 16, this being released from the pin 30 by the spring 29 forcing the lever back into its original position of Figs. 7 and 8. Such slug therefore drops into the slug chute 12 and is discharged.

It will thus been seen that with my slug ejector I have a device which will throw out slugs having magnetic properties no matter whether they have beads on the edge or not, as these do not get into the machine. Slugs which are smooth surfaced are also readily ejected as they are not retained suspended by the holding mechanism. Slugs which have a central aperture and also have a beaded rim are also rejected, such slugs being retained by the device engaging the central aperture and preventing their being positioned over the coin chute and causing their ejection through the slug chute. Legitimate coins however, even if the bead is very much worn are carried through and passed into the coin chute. However, should the bead be entirely eliminated from such coins they will be ejected in the same manner as a smooth slug and returned to the operator of the machine.

As above mentioned this present slug ejector is a modification and in some ways an improvement on that mentioned in my prior application and may be utilized in the same manner with a two coin type of coin controlled machine for vending articles of different prices, or the like, such as set forth in my application Serial No. 22,745, filed April 13, 1925, coin slot mechanism for vending machines.

It will be obvious that my slug ejecting mechanism may be incorporated directly in a coin controlled machine or modified to suit different circumstances. These changes may be in general construction or in specific details and will be within the spirit of my invention as set forth in the description, drawings and claims.

Having described my invention, what I claim is:

10. 1. In a slug ejector, a movable coin or slug carrier, a slug chute, means to delay movement of the carrier at all speeds of movement over the slug chute to allow time for ejection of slugs.
15. 2. In a slug ejector as claimed in claim 14, in which the means to engage the slug comprises a slideable ejector pin and a spring tensioned to press same against the slug when the slug passes adjacent the pin.
20. 3. In a slug ejector, a slideable coin block having a coin pocket therein to receive coins or slugs, a slug chute, a movable means to move the coin block and means to cause a pause in the movement of the block relative to the movable means over the slug chute.
25. 4. In a slug ejector as claimed in claim 3, in which the means to move the coin block comprises a lever having means thereon to give a pausing action in the movement of the block.
30. 5. In a slug ejector having a housing with a longitudinal guideway, a coin block having a coin pocket slideable therein, dogs in the block positioned to engage a coin or slug having a rim on the edge and to convey same suspended in the pocket, a slug chute, a coin chute, means to disengage the dogs from a coin or slug before the coin chute is reached, means to engage a slug having a central aperture and prevent movement of same into the coin chute, the return movement of the block moving the slug with the central aperture into the slug chute.
35. 6. In a slug ejector as claimed in claim 5, the coin or slug being dropped from the dogs on to the base of the guide way, the continuous movement of the block carrying the coin to the coin chute and the reverse movement of the block conveying a slug with an aperture to the slug chute.
40. 7. In a slug ejector as claimed in claim 5, in which the means to engage a slug having a central aperture comprises a pivotally mounted lever having a pin, said pin being slideably mounted in the lever to yield against a solid object, the lever being positioned to be engaged by the block and be operated thereby.
45. 8. In a slug ejector, a guideway having a coin block slideable therein with a coin pocket, the block having a groove in its lower edge, a stationary plate extending upwardly from the base of the guideway to support slugs or coins in the coin pocket, there being a

coin chute thereabove, a slug chute and a coin chute extending downwardly from the base of the guideway, means to move the coin block, gripping means in the block to suspend a coin or slug by a rim, a smooth faced slug rolling on the said plate and dropping into the slug chute, means to disengage the suspending means from a coin and allow same to be discharged into the coin chute on the forward movement of the block, a movable pin positioned to engage a slug having a central aperture after dropping of same from the suspension means, and means to disengage the pin on the reverse movement of the block and allow dropping of said slug with an aperture into the slug chute.

9. In a slug ejector as claimed in claim 8, in which the means to move the block comprises a movable lever having a pausing motion means associated therewith at all speeds of movement.

10. A slug ejector comprising in combination a housing having a coin chute, a guideway in the housing having a slug chute and a coin chute extending downwardly therefrom, a coin block having a coin pocket slideably mounted in the guideway, a plate to retain a coin in the pocket above the bottom of the guideway, suspending means in the block to engage a coin or a slug having a rim, a smoothed faced slug dropping into the slug chute on the forward movement of the block, means to drop a coin or slug having a rim between the slug chute and the coin chute, such coin or slug resting on the base of the guideway, the coin being shoved into the coin chute by the continued movement of the block, a movable pin mounted in the housing to engage a slug having a central aperture and stop the forward movement of the block, means to release said pin on the reverse movement of the block, the said block rolling such slug with an aperture into the slug chute.

11. A slug ejector as claimed in claim 10, having a pin slideably positioned to extend across part of the coin chute, and retaining a coin or slug if the coin block is not positioned therebelow.

12. A slug ejector as claimed in claim 10, having an ejector pin slideably mounted above the block to engage a slug and start the movement thereof into the slug chute.

13. A slug ejector as claimed in claim 10, having a manually operable device to move the block, said device giving the block a pausing movement over the slug chute in either direction of travel.

14. In a slug ejector a movable coin or slug carrier, a slug chute, means to cause a pause in the movement of the coin or slug carrier over the slug chute at all speeds of movement of said carrier, and means to en-

gage a slug and start the movement of the slug out of the carrier into the slug chute.

15. In a slug ejector, as claimed in claim 3, in which the means to move the coin comprise a lever having a U shaped slot, a pin in said slot, the pin being connected to the coin block, the movement of the pin from one part of the U shaped slot to the other allowing the pausing movement of the block.

10 16. In a slug ejector, as claimed in claim 5, in which the means to engage a slug having a bead and a central aperture comprise a pivotally mounted lever having a pin, said pin being slidably mounted in the lever to yield against a solid object, the lever being positioned to be engaged by the block and to be operated thereby, the lever having a spring tensioned normally to draw the pin from the block, the end of the lever adjacent to 20 the spring being positioned to interengage with the block on its forward movement to operate said lever in one direction.

17. In a slug ejector, as claimed in claim 25 8, in which the means to move the block comprise a lever pivotally mounted, said lever having a U shaped slot at one end, a pin fitting in said slot and engaging the block, the said pin being shiftable from one 30 part of the U shaped slot to the other on the swinging movement of the lever and hence allowing a pausing movement of the block during such shifting of the pin in the lever.

18. In a slug ejector, a guideway having 35 a slideable coin block with a coin pocket to receive coins or slugs, a pair of gripping dogs pivotally mounted in the block, said gripping dogs having gripping ends to engage the rim of a coin and to hold same suspended, the pivots of the dogs being 40 parallel to a coin in a coin pocket and the gripping ends being above such pivotal points, forming in effect a toggle with a coin, a slug chute and a coin chute extending 45 below the guideway, means to move the block past the slug chute, the guideway having a base to retain a smooth edged slug in the coin pocket until the slug chute is reached, such smooth slug being allowed to 50 drop into the slug chute, means to disengage the dogs from the coin having a rim before the block is over the coin chute, the guideway having a base on which said coin may drop and roll, the forward movement of the 55 block rolling the coin into the coin chute.

19. In a slug ejector, a guideway having a slideable coin block with a coin pocket to receive coins or slugs, gripping dogs in the block to engage the rim of the coin and to 60 hold same suspended, a slug chute and a coin chute extending below the guideway, means to move the block past the slug chute, the guideway having a base to retain a smooth edged slug in the coin pocket until 65 the slug chute is reached, such smooth slug

being allowed to drop into the slug chute, means to disengage the dogs from the coin having a rim before the block is over the coin chute, the guideway having a base on which said coin may drop and roll, the forward movement of the block rolling the coin into the coin chute, a pivotally mounted lever having a pin mounted in the side of the guideway, means to interengage the lever with the coin block to actuate the lever to engage the pin in a hole in a slug having a bead on the edge and a central aperture and prevent movement of the block over the coin chute, and means operating on the lever to release the pin on the backward movement of the block and allow rolling of the slug with the rim and the aperture into the slug chute.

In testimony whereof I have signed my name to this specification.
